DESIGN FOR A BUTTON

Neil O. Broderson, Rochester, N. Y., assignor to
Rochester Button Company, Rochester, N. Y.,
a corporation of New York

Application January 19, 1940, Serial No. 89,591

Term of patent 7 years

To all whom it may concern:

Be it known that I, Neil O. Broderson, a citizen of the United States, residing at Rochester, in the county of Monroe and State of New York, have invented a new, original, and ornamental Design for Buttons, of which the following is a specification, reference being had to the accompanying drawing, forming part thereof.

In the drawing:

Figure 1 is a plan view of a button showing my new design;

Figure 2 is a transverse sectional view of the same, on the line 2—2 of Figure 1; and

Figure 3 is a transverse sectional view on the line 3—3 of Figure 1.

The dominant feature of the design resides in a button provided with spaced thread holes having connected diamond-shaped configurations on the front face of the button in association with the thread holes.

I claim:

The ornamental design for a button, as shown and described.

NEIL O. BRODERSON.
